UNITED STATES PATENT OFFICE.

CHESTER F. MEYER AND FRANK R. CAMPBELL, OF CLEVELAND, OHIO, ASSIGNORS TO THE NATIONAL MALLEABLE CASTINGS COMPANY, OF CLEVELAND, OHIO, A CORPORATION OF OHIO.

RADIAL-DRAFT GEAR.

1,209,188.

Specification of Letters Patent. Patented Dec. 19, 1916.

Application filed May 18, 1915. Serial No. 28,814.

To all whom it may concern:

Be it known that we, CHESTER F. MEYER and FRANK R. CAMPBELL, both citizens of the United States, and residents of Cleveland, Cuyahoga county, Ohio, have jointly invented new and useful Improvements in Radial-Draft Gears, of which the following is a specification, reference being had to the accompanying drawings, in which—

- 10 Figure 1 is a vertical section of a radial draft gear embodying our invention; Fig. 2 is a horizontal section thereof; Fig. 3 is a section on line III—III of Fig. 1; Fig. 4 is a section on line IV—IV of Fig. 1; Fig. 15 5 is a section on line V—V of Fig. 1; Fig. 6 is a detail section of the outer casing; Fig. 7 is a section on line VII—VII of Fig. 6; Fig. 8 is a detail of the follower.

Our invention relates to radial draft gear, 20 and consists in an arrangement which permits the coupler to buff directly against the shock absorbing mechanism and thereby avoids throwing heavy buffing strains on the parts of the draft member.

25 Our invention also consists in the construction and coöperation of the various parts which we shall hereinafter describe and claim.

Referring to the drawings, A indicates the 30 coupler, B the outer casing of the draft member, C the inner casing of the draft member, D the shock absorbing mechanism which we have shown in the form of a friction barrel, and E the follower.

35 The outer casing B has a forward extension in the form of a pocket 2, for reception of the coupler shank 3. The rear end of the pocket 2 terminates in a rectangular opening 4 for admission of the coupler liner 40 block 5 and the guiding lugs 6, 6 of the inner casing C, which project forwardly through the opening 4 above and below the coupler liner block when the gear is under buffing stress. The forward end of the inner 45 case C likewise has an opening 7 for admission of the liner block 5, so that it may abut directly against the forward end of the friction mechanism D.

The rear portion of the outer casing B is 50 preferably cylindrical throughout its length and is enlarged at its rear end. Upon the inner wall of this enlarged portion are segmental pulling lugs 8, preferably one on each side, which occupy a little less than

one-half of the inner periphery of the case, 55 as will presently be explained.

The inner casing C has a cylindrical forward portion which has a bearing when under heavy buff at its forward end against the shoulders 4' at each side of the opening 60 4 in the casing B, and contains the friction mechanism D, as is shown in Figs. 1 and 2, and also rearwardly-extending vertically-alined arms 9, 9, apertured for a pivot pin 10. The lower arm 9 is provided with aper- 65 tured ears 11, to support a pivot pin retainer.

The follower E at its rear side is formed with a concave buffing surface 12, which bears against a similarly-curved convex surface upon the pivot casting 13. The forward face 14 of the follower E is designed to abut directly against the rear end of the friction mechanism D. The follower E also has on each side outwardly-extending seg- 70 mental pulling flanges 15, adapted to co- 75 operate with the lugs 8 of the outer casing B in the manner later to be described.

In assembling the draft member, the friction mechanism is inserted into the inner casing C from its rear end passing between 80 the arms 9. The casing C is then inserted into the outer casing B, the two casings being temporarily so alined that the arms 9 of the inner casing lie in the same plane as the pulling segments 8 of the outer casing B, 85 and with its guiding lugs 6 bearing against the shoulders 4' of the outer casing. The follower E is then inserted between the arms 9 of the casings, with its flanges 15 at right angles to the plane of the arms 9 and seg- 90 ments 8, into contact with the friction mechanism D. The inner casing C and with it the friction mechanism D and follower E are next rotated 90 degrees while the outer casing is held stationary, thus bringing the 95 segments 8 on the outer casing and flanges 15 on the follower into alinement with each other, so that the projections 16 will be brought into register with the correspond- 100 ing notches 17 in the segments 8, and the alinement between these parts will thereby be secured. The turning of the inner case C will also bring the lugs 6 into alinement with the opening 4 in the forward end of the cylindrical portion of the case B. The 105 coupler A may then be placed in the pocket and skidded rearwardly, the liner block 5 passing through the opening 4 between the

guiding lugs 6 and through the opening 7 at the forward end of the inner case C, until it presses directly against the closed end of the friction case and pushes it and the following 5 lower E rearwardly. By inserting keys 18 through the slots 19 in the shank pocket so as to lock the coupler in place, the outer casing is drawn forwardly and at the same time the coupler will hold the friction mechanism 10 and through it the follower E from forward movement, so that the segments 8 on the outer casing B and the flanges 15 on the follower will fit snugly together and will be held in alignment by the projections 16 and 15 notches 17.

The operation of the device is as follows: In draft the coupler pulls the outer casing B forwardly, and the casing B, through the engagement of its segments 8 with the 20 flanges 15 of the follower, pulls the follower forward. The follower in turn compresses the friction elements within the friction casing D, which is held against forward movement by its bearing against the forward end of the inner casing C, which is held stationary by the attachment of its arms 9 to the pivot pin and pivot casting 13. The pulling stresses are therefore transmitted from the coupler to the car as follows: from coupler to outer casing B, from 25 outer casing B to follower E by segments 8 and flanges 15; from follower to friction mechanism D; from friction mechanism to inner casing C; from inner casing by arms 30 9 to pivot pin, pivot casting and to car. In buff the coupler liner block bears directly upon the friction case D and drives it rearwardly, so that the follower E, which is held stationary by the pivot casting, will force 35 the friction elements into the case and the buffing shocks will thereby be taken up. The outer casing B is carried rearwardly with the coupler A sliding upon the inner casing C, but is not under stress, while the inner casing C, as in draft, remains stationary as it is pivoted by its arms 9 to the pivot casting 13. It will therefore be seen that the outer casing B and the inner casing C are under stress only in draft, and that the 40 heavy buffing blows transmitted from the coupler are taken up directly by the shock-absorbing mechanism and are thence transmitted by the follower E to the pivot casting on the car, until the friction rigging 45 goes "solid," after which the remaining stresses are transmitted through the shoulders 20 on the outer casing B directly to the follower. The shoulders 4' also strike the forward end of the inner casing at the same 50 time, thus distributing the stress between the two casings and the friction gear. The casing C is held from twisting by reason of the connection of its arms 9 to the pivot pin, and the rectangular opening 7 and the 55 lugs 6 keep the coupler from twisting with

respect to the casing C. The coupler butt, however, under heavy draft stresses, is pulled forward of the flanges or lugs 6, 6 of the casing C, so that the coupler and outer casing A would be free to twist were it not for the notches 17 in segments 8 and projections 16 in the flanges 15 on the follower. The follower E is held from twisting by the arms 9 of the casing C. The guiding lugs 6, 6 of the inner casing are flared outwardly, 75 to assist in guiding the coupler butt to the rectangular opening 7 in the forward wall of the casing C, and also serve to maintain the device in alignment in case the friction mechanism should fail to release. The friction mechanism would then remain under partial compression, and the corresponding amount of longitudinal play might, without the lugs 6, permit the coupler butt to get out of alignment with the rectangular opening in the forward end of the casing C. 80

The terms and expressions which we have employed are used as terms of description and not of limitation, and we have no intention, in the use of such terms and expressions, of excluding any mechanical equivalents for the features shown and described, but recognize that various structural modifications are possible within the scope of the invention claimed. 95

What we claim is:

1. In a radial draft gear, a casing pivoted to the car body, containing a shock absorbing mechanism, a second casing having a telescoping engagement with the first named casing, a coupler adapted to move with the second named casing, and an opening in the first named casing to permit the rear end of the coupler during buffing to move therethrough into direct contact with the shock absorbing mechanism. 100

2. In a radial draft gear, a casing pivotally connected to a car containing a shock absorbing mechanism, a follower having a bearing on the shock absorbing mechanism 110 and engaging a second casing, the follower and the second named casing having a recess and projection engagement to prevent a twisting movement of the second named casing. 115

3. In a radial draft gear, a casing adapted to be pivotally mounted on a car and containing a shock-absorbing mechanism, a second casing having a plurality of inwardly-extending lugs, and a follower having a plurality of outwardly-extending flanges, the lugs and flanges being adapted to be rotated into engagement during assembly of the gear. 120

4. In a radial draft gear, a casing adapted to be pivotally mounted on a car and containing a shock-absorbing mechanism, a second casing having a plurality of lugs, and a follower having a plurality of flanges, the follower being adapted to be inserted into 125 130

- the second casing and to be rotated to bring the flanges into alinement with the lugs, the lugs and flanges comprising means for locking the parts of the gear together.
5. In a radial draft gear, a casing pivotally connected to a car, shock absorbing mechanism contained therein, a second casing having projections, a coupler connected to said second casing, a follower normally in engagement with the car and having projections adapted to have a pulling engagement with the projections on said second casing, a plurality of sets of shoulders on said second casing, one of said sets being adapted to have a buffering engagement with the follower, and another of said sets to have a buffering engagement with the first named casing, whereby excessive buffering shocks are distributed between said follower and said first named casing, to relieve the shock absorbing mechanism of excessive strain.
10. In a radial draft gear, a casing pivotally connected to a car, shock absorbing mechanism contained therein, a second casing having projections, a coupler connected to said second casing, a follower normally in engagement with the car and having projections adapted to have a pulling engagement with the projections on said second
